L. W. EGGLESTON

VALVE

Filed July 30, 1923

Lewis W. Eggleston
BY C. M. Reglman
his ATTORNEY.

UNITED STATES PATENT OFFICE.

LEWIS W. EGGLESTON, OF BUFFALO, NEW YORK, ASSIGNOR TO AMERICAN RADIATOR COMPANY, OF NEW YORK, N. Y., A CORPORATION OF NEW JERSEY.

VALVE.

Application filed July 30, 1923. Serial No. 654,598.

My invention relates broadly and generally to new and useful improvements in thermostatically operated valves, and particularly contemplates the provision of a valve to be employed as an air vent valve for steam heating systems; that is, a valve which will automatically function to permit air to pass from a steam heating system when the steam is turned on, and to close promptly when the air has been vented and the steam reaches the valve.

The primary object of the invention, among others which will be apparent from the following detailed description, is to provide a valve of the character above set forth, which will be inexpensive to manufacture, simple in construction, and which will be sensitive and efficient in operation.

The invention consists in the improved and novel construction of parts, and their aggroupment in operative combination, to be more fully described hereinafter, and the novelty of which will be particularly pointed out and distinctly claimed.

I have fully and clearly illustrated a preferred embodiment of my invention in the accompanying drawings, to be taken as a part of this specification, and wherein—

Figure 1 is a vertical longitudinal central section view;

Fig. 2 is an enlarged view in elevation, partly in section, of an expandible-collapsible element forming one of the parts of the invention;

Fig. 3 is detail sectional view of a valve carrier;

Fig. 4 is a longitudinal sectional view of a guide or centering member;

Fig. 5 is a longitudinal sectional view of a guide sleeve adapted to cooperate with the member shown in Fig. 4, and

Fig. 6 is a detail sectional view of a supporting device for the element shown in Fig. 2.

Referring to the drawings by characters of reference—

1 designates generally a valve body or casing which may be of any suitable external contour. The valve body is formed with an upper cylindrical extension 2 forming a chamber 3 communicating with the interior of the body 1, said extension being open at its upper end, as at 4. The body is provided with a lateral inlet connection 5 for connection to a steam system, and with an out-

let connection 6, the latter being in line with the chamber in the body and the extension 2. Within the body 1, and preferably surrounding the port or connection 6, is an annular valve seat 7 facing toward the interior 60 of the body.

Arranged within the body and adapted to cooperate with the seat 7 is a valve member and means for thermostatically controlling the same, said valve and means being 65. preferably in a unitary structure which permits convenient assemblage of the same in the body, and ready withdrawal therefrom when desirable or necessary. The structure just mentioned comprises an expandible-collapsible element, preferably in the form of a cylindrical metallic shell 8 having annular corrugations 9 rendering the same longitudinally elastic or resilient. In the preferred form, this element 8 is closed at its 75 upper end by an integral head in the form of a central cylindrical boss 10 having a cylindrical wall 11 coaxial with said element, and having an end wall 12 extending transversely of the element. The opposite 80 or lower end of the element, during manufacture thereof, is provided with a longitudinal flange 13, the purpose of which will be presently set forth.

At its lower end the element 8 is closed by a head or closure 14, which also constitutes a valve carrier. This head 14 is circular in top, plan view, and is provided with a circumferential, rounded bead 15, the element and head being connected by applying the 90 flange 13 to said bead and rolling the same into close, sealed contact therewith, as shown at 16 in Fig. 1. The joint may be additionally sealed against leakage by solder or other suitable means.

The head 14 is provided on its face toward the valve seat 7 with a circumferential flange 17, and a central, hollow stud 18, thereby forming an annular seat 19, in which is seated a valve disk 20, the latter being held 100 in place by a clamping nut 21, threaded, as at 22, onto the lower end of said stud 18. It will be seen that the element 8, together with the closure head 14 and the head 12, 105 form a sealed chamber, which is longitudinally expandible and collapsible, and when evacuated to the desired degree of subatmospheric pressure and charged with a suitable volatile liquid, constitutes a thermostatic element. The evacuated element is 110

charged with any suitable volatile liquid which will vaporize to furnish pressure to actuate the element 8 when the latter is heated to a determined degree. A volatile liquid is selected which will volatilize at the temperature at which it is desired the valve shall operate, say, for example, 180° F. or 200° F., in which case alcohol, or a mixture of alcohol and water, may be used. The element is evacuated and charged through a charging tube 23, sealed in a bore 24 passing through the head 14 and the stud 18, said tube being afterwards pinched together and suitably sealed, as at 25. If desired, the tube 23 may be sealed in said bore 24 by means of solder 26 deposited in a recess 27 in the head 14, and surrounding said tube.

At the end opposite the valve, the element 8 is provided with means carried thereby for supporting and fixing the same in position in the valve body. The means just mentioned preferably consists of an annular sleeve 28 tightly fitting the cylindrical wall 11, and secured thereto by a solder joint 29, said sleeve having at its lower end an outwardly directed, lateral flange 30, which, when the valve is assembled, rests upon the upper edge of the extension 2 of the valve body. The flange 30 is clamped in position on the body by means of a cap 31 having an annular depending flange 32 formed with internal screw threads adapted to interengage with external threads on the body, as shown at 33. The closure cap is provided with an internal annular face 34 which seats on the upper face of flange 30 and by which the flange is clamped rigidly in position when the cap is screwed into assembled position.

It is to be noted that the flange 30 is located beneath the head 12, so that the boss 10 projects above the upper end of the extension 2, where it may be conveniently grasped when the structure is to be removed from the valve body. The cap 31 is provided with an internal chamber or recess 35 to accommodate said boss when the parts are assembled, as shown in Fig. 1. It is also to be noted that the element 8 and the valve carried thereby are supported solely by said flange 30, so as to move freely in the casing or body.

I also provide simple and efficient means for maintaining the valve properly centered in the body, and guiding it in its movement toward or away from the seat 7. This means preferably comprises means arranged within the element 8, and includes a cylindrical member 36 coaxial with and extending lengthwise of said element, said member being snugly fitted within the boss 10, as at 37, and secured thereto by solder or other desired means. The opposite end of said member 36 from that just described, terminates adjacent, but slightly removed from, the valve part 14, so that said end will not

engage said part during movement of the valve.

The valve part is provided on its inner or upper face with a central, cylindrical boss 37, upon which is seated the lower end of a 70 guide member in the form of a sleeve 38, which telescopically cooperates with the lower end portion of the member 36 heretofore described, said sleeve 38 being preferably arranged within the member 36. The 75 sleeve or member 36 is preferably of such diameter as to closely approach but not contact the inner bends of the corrugations of the element 8, so as not to retard the free longitudinal movement of said element, but to 80 prevent lateral deflection of said element. The sleeve 38 is preferably of such diameter that the outer face closely approaches the inner face of the member 36, but does not touch the same, so as to avoid any engagement between said member and sleeve as might retard free movement of the element 8. The length of the sleeve 38 is preferably 85 such that the engagement of said sleeve and member 36 is of sufficient extent to assure 90 proper presentation at all times of the valve to its seat.

The device being constructed as above described, the operation thereof is as follows. the parts being shown in Fig. 1 in the position assumed when the temperature at that point in a system is below that at which the element 8 expands to close the valve: When steam is turned into the system it flows through the usual piping (not shown) to the inlet 5, forcing in front of it air which may exist in the piping, this air entering the valve body through the inlet 5 and out through the outlet 6. The steam reaching the interior of the valve body flows into contact with element 8 and heats the volatile liquid therein. As soon as the vaporization of the volatile liquid generates sufficient pressure, the element 8 expands and moves the valve disk toward and in engagement with its seat, thereby closing the outlet 6 and preventing escape of steam. When the steam is turned off in the system, the temperature adjacent element 8 eventually drops to a point below the vaporization 105 point of the volatile liquid in said element, which results in a reduction of pressure, permitting the element to collapse and lift the valve from its seat, as shown in Fig. 1.

It will be readily seen that the thermostatic element, its supporting means, the valve, and the guiding means, are in a unitary structure, which greatly facilitates assembly of the parts in, and removal from, the valve body. The unitary structure described also has the advantage that a very simple form of valve body may be employed.

What I claim and desire to secure by Letters Patent of the United States is:—

1. In a device of the character described,

- a valve casing having ports and a valve seat, said casing having an open end portion surrounded by a shoulder, a unitary thermostatically operable valve structure bodily insertible in and removable from the casing, said valve structure comprising a tubular expansible-collapsible thermostatic element in said casing and having circumferential corrugations, an integral head closing one end of said element and comprising an outwardly projecting boss including a cylindrical wall coaxial with said element and an end wall extending transversely of said element, a flange member carried by said boss at a point removed from the end wall thereof, said flange being arranged to rest on said shoulder and said boss to project beyond the open end portion of the casing to constitute a hand grasp, means for securing said flange on said shoulder, and a closure for the opposite end of said element and carrying a valve cooperable with said seat.
2. In a device of the character described, a valve casing having ports and a valve seat, said casing having an open end portion surrounded by a shoulder, a unitary thermostatically operable valve structure bodily insertible in and removable from said casing, said structure comprising a tubular expansible-collapsible thermostatic element in said casing and having circumferential corrugations, an integral head closing one end of said element and comprising an outwardly projecting hollow boss, a flange member carried by said boss at a point removed from the end thereof, said flange being arranged to rest on said shoulder and said boss to project beyond said open end portion of the casing and constituting a hand grasp, a closure cap separate from said element and closing said casing and securing said flange on said shoulder, a closure for the opposite end of said element and carrying a valve cooperable with said seat, an internal projection on said closure, and means within said element for guiding said valve relative to its seat, said means including a sleeve rigidly secured in said hollow boss, and a second sleeve secured to said projection and telescopically coacting with said first-named sleeve.
3. In a device of the character described, a valve casing having ports and a valve seat, said casing having an open end portion surrounded by a shoulder, a unitary thermostatically operable valve structure bodily insertible in and removable from said casing, said structure comprising a tubular expansible-collapsible thermostatic element in said casing and having circumferential corrugations, an integral head closing one end of said element and comprising an outwardly projecting boss including a cylindrical wall coaxial with said element and an end wall extending transversely of said element, a flange member carried by said boss at a point removed from the end wall thereof and including an annular sleeve secured to said cylindrical wall and provided at its lower edge portion with an outwardly directed lateral flange, said flange being arranged to rest on said shoulder and said boss projecting beyond said open end portion of the casing and constituting a hand grasp, means for securing said flange on said shoulder, and a closure for the opposite end of said element and carrying a valve cooperable with said seat.

In testimony whereof I have hereunto subscribed my name.

LEWIS W. EGGLESTON.
